UNITED STATES PATENT OFFICE.

CHARLES B. WESTBROOK, OF NEWTON, IOWA.

LACE-CURTAIN-DISPLAY CABINET.

No. 844,432.

Specification of Letters Patent.

Patented Feb. 19, 1907.

Application filed August 20, 1906. Serial No. 336,308.

To all whom it may concern:

Be it known that I, CHARLES B. WESTBROOK, a citizen of the United States, residing at Newton, in the county of Jasper and State of Iowa, have invented a new and useful Lace-Curtain-Display Cabinet, of which the following is a specification.

My object is to provide improved, simple, strong, durable, convenient, and efficient means in a portable cabinet for concealing and protecting lace curtains and like fine textile fabrics, and specially adapted for displaying such merchandise in a store to customers whenever desired.

My invention consists in the structure hereinafter set forth, pointed out in my claim, and illustrated in the accompanying drawings, in which—

Figure 1 is a top view of the cabinet in an open position. The top board covers of the two parts are removed. Dotted lines indicate curtain-bearers hinged to the hinged sections of the cabinet, that can be swung out and separated as required to display curtains suspended thereon. Fig. 2 is an inside face view of one of the sections of the cabinet and shows how brackets or curtain-bearers are pivotally and adjustably connected with the backs of the cabinet-sections by means of square flat boards or carriers hinged to the inner sides of the front edges of the backs of the hinged sections.

The numerals 10 designate the closed back walls, 12 the bottoms, 13 the tops, 14 the rear upright parts, and 15 the front upright parts, of the two sections of the cabinet, that are hinged together, as shown in Fig. 1, or in any suitable way in such a manner that they can be turned apart as required to open and close the cabinet at pleasure.

It is obvious that the cabinet may vary in size and be made of boards or other suitable material and used for protecting and displaying smaller articles of textile goods than curtains.

When used for lace curtains, the sections are preferably seven feet high, five feet wide, and twelve inches at their sides, tops, and bottoms.

The two sections are hinged together at the inner edges of their rear upright parts 14 by hinges 16, and 17 is a latch device or turn-button on the front upright 15 for fastening the two sections together when in a closed position.

Square flat boards 18 are hinged direct to the top end portions of the front edges of the rear uprights 14 by hinges 19, as is required, in order to be folded into the sections or turned outward, as is indicated by dotted lines in Fig. 1, and to the faces of these hinged boards are pivotally connected a plurality of brackets or curtain-bearers 20 by means of fixed hinge-irons 21 and rods 22, as shown in Fig. 2, or in any suitable way in such a manner that the curtain-bearers will extend horizontally relative to their hinged supports 20 and the hinged cabinet-sections.

Cords 23, having weights 24 at their free ends are attached to the tops of the insides of the rear walls of the hinged sections in such a manner that they will normally retain the curtain-bearers 20 close together in parallel position. To swing a curtain-bearer outward and away from the others, as required for displaying a curtain hanging thereon, the cord must be lifted to allow the curtain-bearer to be moved outward and away from the others.

Casters 25 are attached to the bottoms 12 of the two hinged sections to facilitate their movements relative to each other and also for moving about the entire cabinet.

Having thus set forth the purposes of my invention and its construction and manner of use, the practical operation and utility thereof is obvious.

What I claim as new, and desire to secure by Letters Patent, is—

A cabinet for lace curtains and the like comprising two sections each composed of a bottom, a top, two straight sides and a back all fixed together and the top sections hinged together at the front edges of their rear upright sides, a flat board hinged direct to the top portion of each of said upright sides to swing horizontally and a plurality of curtain-bearers pivotally connected direct with said hinged boards to swing horizontally, cords fixed to the hinged sections under their tops to extend over the free end portions of the curtain-bearers and weights on their ends, to retain the curtain-bearers together in parallel position, as set forth.

CHARLES B. WESTBROOK.
